UNITED STATES PATENT OFFICE.

WILLIAM B. MANGOLD, OF CHICAGO, ILLINOIS, ASSIGNOR TO THE VORTEX MFG. CO., A CORPORATION OF ILLINOIS.

CUP DISPENSER.

Application filed August 1, 1923. Serial No. 654,988.

This invention relates to a cup dispenser, and more particularly to a dispenser for flat cups of sector-shape adapted to be placed in a stack in inclined position within a slotted 5 container having a back closure plate and a cover which are pivotally supported on a mounting plate on which the cup container is also pivoted, said container adapted to be held in closed position by its cover and when 10 in open position adapted to be resiliently held slightly inclined by means of a spring member.

It is an object of this invention to provide a flat cup dispenser wherein a pivoted container is adapted to be retained in place by the container cover.

It is also an object of this invention to provide a flat cup dispenser wherein a pivoted cup container, when in open position for 20 filling, is adapted to be resiliently held in an inclined position by a spring stop member.

It is a further object of the invention to provide a flat cup dispenser wherein a pivoted container is provided with a pivoted 25 back closure plate having means movably mounted thereon for properly positioning or leveling the flat cups within the container before the filled container is swung upwardly into closed position.

Another object of the invention is to provide a dispenser for flat cups, said dispenser embracing a cup container pivotally mounted and having a pivoted back plate equipped 30 with a cup straightener and with a latching mechanism for holding the back plate locked to the container in closed position, said straightener adapted to be held in position at the upper end of the back plate by the handle of the latching mechanism.

It is furthermore an object of this invention to provide a flat cup dispenser wherein a cup container and the cover thereof are pivotally supported on opposite ends of a mounting plate.

Another object of the invention is the providing of a flat cup dispenser wherein a cup container is equipped with a plurality of back plates, one of which serves as a mounting for the dispenser, while the other is adapted to be removably locked to the container for holding flat cups in proper dispensing position.

It is an important object of this invention to provide a flat paper cup dispenser of improved construction wherein a flat cup con-

tainer is provided with double back plates, the inner back plate having a locking mechanism and a cup straightening device mounted thereon, while the outer back plate is apertured to permit the same to be rigidly secured to a wall and has a container cover pivoted thereon adapted to engage and hold the container in position to permit the flat cups to be readily removed from the lower slit portion of the container.

Other and further important objects of this invention will be apparent from the disclosures in the specification and accompanying drawings.

This invention (in a preferred form) is 70 illustrated in the drawings and hereinafter more fully described.

On the drawings:

Figure 1 is a front elevation of a flat cup dispenser embodying the principles of this 75 invention.

Figure 2 is a side elevation of the dispenser supported on a wall ready for use.

Figure 3 is an enlarged transverse section taken on line 3—3 of Figure 1.

Figure 4 is an enlarged longitudinal section taken on line 4—4 of Figure 1 with parts in elevation.

Figure 5 is a fragmentary central vertical section through the dispenser in open position, showing the method of properly positioning the flat cups within the container.

Figure 6 is a plan view of the inner side of the container cover.

Figure 7 is an enlarged view of the container when in open position taken on line 7—7 of Figure 5.

Figure 8 is an enlarged fragmentary detail section taken on line 8—8 of Figure 4.

Figure 9 is an enlarged fragmentary detail section taken on line 9—9 of Figure 2.

Figure 10 is a reduced section taken on line 10—10 of Figure 4.

As shown on the drawings:

The reference numeral 1 indicates a wall 100 or support upon which a flat cup dispenser of this invention is mounted in position for use. The dispenser comprises a flat outer back plate 2 made of metal and having a plurality of apertures 3 therein, for receiving mounting screws for the purpose of rigidly securing the dispenser to the wall 1 or on any other support. The back plate 2 is provided with integral forwardly directed longitudinal flanges 4, each of which is pro-

vided with a notch 5 near the upper end thereof. The lower end of the outer back plate or mounting plate 2 is provided with an integral extension to afford a back stop 6 apertured at 7 to receive a retaining screw. The upper edge of the back plate 2 is provided with two spaced integral hinge sleeves 8.

A cover plate 9 is provided for the dispenser. Integrally formed on one edge of the cover plate 9 are a plurality of hinge sleeves 10 between which the hinge sleeves 8 of the back plate are positioned. A hinge pin or rod 11 projects through the aligned hinge sleeves 8 and 10 to hold the cover plate pivoted to the upper edge of the back plate 2. The cover plate 9 is shaped to have two inclined edges 12 which converge to join a front edge having a latch flange or tongue 13 integrally formed thereon at right angles to said cover plate. Secured to the inner face of the cover plate 9 is a sector shaped plate 14 having integral flanges 15, 16 and 17 (Figure 4) which rest against the inner face of the cover plate at a distance from the edges thereof. Secured to the sector plate 14 at the middle portion of the curved edge 18 thereof is a projecting lug or tab 19 which is opposite the latch flange 13.

Supported by the lower ends of the back plate flanges 4 is a shaft or rod 20, the threaded ends of which are threaded into headed sleeves 21 (Figure 9) which are rotatable with respect to the flanges 4. Secured to the rotatable sleeves 21 to the outside of the back plate flanges 4 are the lower ends of a pair of longitudinal casing or container flanges 22. The flanges 22 are integrally formed along the longitudinal edges of a casing or container adapted to hold a stack of flat paper cups 23. The paper cups are folded flat and are of sector shape with the tips bent over flat against one side of the cups. The flat cup container is made of metal or other suitable material and consists of two inclined side walls or plates 24 which converge to integrally join the longitudinal edges of a narrow front plate 25 having a plurality of aligned sight apertures or slots 26 therein. Each of the container side plates 24 is provided with an upwardly and rearwardly inclined slot 27 which extends from the front plate 25 to within a short distance of the container flange 22. The lower front corners of the container side plates 24 are cut or bent inwardly at 28 to afford an index finger recess below the lower front end of the container. The lower end of the container front plate 25 is rounded and bent outwardly to form a thumb piece 29 which is disposed in front of the middle portion of the finger recess 28. The upper margins of the container side plates 24 and the front plate 25 are bent inwardly at right angles to form a narrow flange 30 adapted to be

frictionally engaged by the flanges 15, 16 and 17 of the cover liner plate 14 when the cover is lower to close the upper end of the container. In the closed position of the cover the latch flange 13 frictionally engages the outer surface of the upper end of the container front plate 25, thereby holding the container locked in a vertical dispensing position (Figures 1 and 4).

Secured to the inner surfaces of the container side plates 24 below the inclined slots 27 are the flanges 31 of a downwardly curved or concave cup supporting shelf 32. The cup shelf 32 is cut away as at 33 in the form of an arc of a circle so as to permit the bent over ends of the flat cups 23 to project into the recess 28 to the rear of the thumb piece 29 as illustrated in Figure 5. Rigidly secured to the bottom of the cup supporting shelf 32 is a looped stop spring 34 adapted to abut the stop plate 6 when the container is in open position to resiliently hold said container in a slightly inclined position as shown in Figure 5.

Pivotedly supported on the sleeves 21 to the inside of the back plate flanges 4 are the lower ends of a pair of flanges 35 reinforced at their pivoted ends by reinforcing strips 36 secured to said flanges by rivets or other suitable means. The flanges 35 are integrally formed on the longitudinal edges of an inner back plate 37 which is curved or outwardly convex. The inner back plate 37 is provided with a central longitudinal slot 38 in which a cup positioning shoe is slidably mounted. The cup positioning shoe comprises a looped or rounded head 39 forming a portion of a strip of metal which is secured to a block 40 slidable within the slot 38 (Figure 4). Also secured to the block 40 on the outside of the back surface of the inner back plate 37 is a toothed or knurled handle or finger plate 41 to facilitate sliding of the shoe by hand when the container is in open position. The inner back plate 37 is adapted to close the rear of the cup holding container and is provided at its upper end with a locking or latching mechanism. The locking mechanism comprises a plate 42 which is rigidly secured to the back of the upper portion of the inner back plate 37 above the upper end of the slot 38. The back plate 42 is slit transversely and has the side margins curled outwardly and then inwardly to form sleeves 43, the lower ends of which are shaped to afford cam edges 44. Portions of the side margins of the back plate 42 are also bent outwardly and then inwardly to form rounded spreader lugs or locking members 45. The sleeves 43 are apertures to permit locking rods 46 to slidably project therethrough. The inner ends of the locking rods 46 are integral with a looped spring handle 47 adapted to co-act with the spreader lugs 45 so that when the

Handle is swung toward the plate 37 the handle arms will be sprung or forced apart, thereby causing the locking rods to slide outwardly so that the ends thereof which 5 project through apertures in the plate flanges 35 will lockingly engage behind stop blocks 48 which are rigidly secured to the inner surfaces of the container flanges 22. When the handle 47 is moved away from 10 the plate 37 the handle arms co-act with the cam edges 44 of the sleeves 43 and are moved inwardly toward one another to draw the locking rods 36 inwardly out of locking engagement with the locking blocks 48. When 15 the handle 47 is in locking position it surrounds the finger plate 41 and serves to hold the cup positioning shoe in place.

The operation is as follows:

The flat cup dispenser of this invention 20 is intended for use in Pullman cars, railway coaches, adjacent drinking fountains and in other places where drinking water is provided.

The dispenser is mounted on the wall 1 by 25 securing the outer back plate 2 in place by retaining screws engaged through the apertures 3. This can be done when the cover is raised and the container is lowered as illustrated in Figure 5.

30 For the purpose of filling the container with flat paper cups 23, the lock handle 47 is lifted or swung away from the inner back plate 37 until the handle arms are brought into contact with the cams 44 which serve 35 to cause the handle arms to be forced toward one another, thereby drawing the ends of the locking rods 46 inwardly out of locking engagement with the blocks 48. The inner back plate 37 is thus unlocked and is 40 swung upwardly into vertical position against the outer back plate 2. When the inner back plate 37 is moved into open position the cup straightening shoe drops by gravity to the lower end of the slot 38.

45 The cup container is now open and is resiliently held in a slightly inclined position, due to the looped spring 34 pressing against the stop plate 6. A stack of flat sector shaped cups 23 are now removed from 50 a carton and deposited in the open container taking a position similar to the cups in position "A" Figure 5. In order that the cups may be properly removed from the container they should be positioned in inclined planes 55 parallel to the plane of the container outlet slots 27. The inner back plate 37 is lowered to close the back of the lowered container and the cup positioning shoe mechanism is manually moved from the lower end of the 60 slot 38 to the upper end thereof, thereby causing the looped head 39 to push the cups from the position "A", Figure 5, into their proper discharging position "B" in planes parallel to the plane of the container slots 27. 65 The lock handle is now swung into locking

position so that the handle arms, when engaging the lugs 45, are forced away from one another, thereby forcing the locking rods outwardly behind the locking blocks 48 to hold the inner back plate lock to the container. 70 The handle 47, when in locking position (Figure 7), engages around the finger piece 41 of the cup positioning shoe to hold the same in place.

75 With the container filled with flat paper cups properly inclined, the container is swung upwardly together with the inner back plate into a vertical position against the outer back plate 2 with the outer back plate flanges 4 positioned between the flanges 22 and 35. The notches 5 are provided in the flanges 4 to afford a clearance for the lock blocks 48 and the ends of the locking rods 46. With the filled container raised 80 into a proper dispensing position, the container cover 9 is swung downwardly with the liner flanges 15, 16 and 17 frictionally engaging the container flanges 30, while the latch flange 13 frictionally engages over the outer surface of the upper end of the front wall 25 of the container. When the cover is closed the lug 19 supported on the inner side of the cover, is forced against the inner surface of the upper end of the inner back plate 37 to assist in holding the cover 90 in closed position to hold the container locked against falling forwardly into open position.

85 The wide portions of the flat cups within the container are positioned a little to the rear of the upper ends of the slots 27 with the side margins of the lowermost cup resting on the side margins of the concave shelf 32. To remove a cup from the container it is only necessary for a person to place a 90 thumb against the thumb piece 29 and the index finger in the recess 28 against the folded end of the lowermost cup in the container. Pressure against the folded end of the lowermost cup causes said cup to slide 95 outwardly while the wide end of the cup is buckled against the curved shelf 32 until the wide end of the cup passes into the slots 27. The cup is now easily pulled out of the container against the pressure caused by the 100 weight of the cups within the container. With the removal of a cup from the container the remaining cups drop by gravity 105 in the container ready for the removal of the next cup. The slots 26 in the front of the 110 container afford a means whereby an attendant may be advised when the supply of cups within the container is nearly depleted.

115 I am aware that many changes may be made, and numerous details of construction 120 may be varied through a wide range without departing from the principles of this invention, and I therefore do not purpose limiting the patent granted hereon, otherwise than necessitated by the prior art. 125 130

I claim as my invention:

1. A flat cup dispenser comprising a mounting plate adapted to be rigidly secured to a wall, a cup container pivoted to one end of the mounting plate for holding a stack of cups with the cups inclined with respect to the container walls, a back closure plate for the container pivoted on the same end of said mounting plate, looped spring means slidable on said back closure plate for increasing the inclination of cups in said container, and a cover for the container pivoted on the other end of said mounting plate.
2. A flat cup dispenser comprising a mounting plate adapted to be rigidly secured to a wall, a cup container pivoted to one end of the mounting plate, a back closure plate for the container pivoted on the 20 mounting plate, means slidably mounted on said back closure plate for tilting cups in said container, a cover for the container pivoted on the other end of the mounting plate, and means at the pivoted end of the 25 container for facilitating the withdrawal of cups from the container.
3. A flat cup dispenser comprising a container adapted to hold a stack of flat paper cups, a plurality of back plates pivotally connected to said container, and a cover for the container pivotally mounted on one of said back plates.
4. A flat cup dispenser comprising a container having sight apertures and cup discharge slots therein, a pair of back plates pivotally connected to said container with one of said plates adapted to be secured to a wall to afford a support for the container, and a cover for the container pivotally supported on the wall plate.
5. A flat cup dispenser comprising a mounting plate adapted to be secured to a wall, a cup container pivoted on one end of said mounting plate and having sight apertures and cup outlet slots therein, a back closure plate for the container pivoted to the same end of the mounting plate, means slidably mounted on said back closure plate adapted to adjust and level the 50 cups in said container, and a locking mechanism on said back closure plate adapted to hold said back closure plate locked to the container.
6. A flat cup dispenser comprising a mounting plate adapted to be secured to a wall, a cup container movably supported on one end of the mounting plate, a container cover movably supported on the opposite end of said mounting plate, a slotted back plate for the container movably supported on the same end of the mounting plate on which the container is supported, cup leveling means slidably mounted on said slotted back plate, a locking mechanism on said back plate, and a handle for operating

the locking mechanism to lock the back plate to the container and hold said cup leveling means at one end of said back plate.

7. A flat cup dispenser comprising a cup container, a support therefor, a back closure plate for the container pivoted on said support, and a shoe slidably mounted on said closure plate adapted to be pushed from one end of said plate to the other to move the 75 cups within the container into predetermined inclined planes.

8. The combination with a container for holding a stack of flat paper cups, of looped spring means slidably projecting into the 80 container for leveling the cups and moving the same into planes to facilitate removal of the cups from the container.

9. The combination with a cup container, of a closure plate pivotally connected thereto, means slidably mounted on said plate for adjusting the cups in said container so that the cups will be positioned in parallel inclined planes and in a straight stack within the container, and means for locking said plate to the container and also adapted to hold said means at one end of its path of movement.

10. A flat cup dispenser comprising a pivotally supported cup container, a back closure plate pivotally connected to one end of the container, locking blocks secured in the opposite end of the container, a cup leveling means slidable on said closure plate, and locking mechanisms on said back plate adapted to be operated to engage behind said locking blocks to hold the back plate locked to the container and further adapted to hold said cup leveling means at one end of its path of movement.

11. A cup dispenser comprising a pivotally supported cup container, a closure plate pivotally connected thereto, a slideable cup leveler on said closure plate blocks rigidly secured in said container, locking rods 110 supported on said plate, a handle connecting said locking rods and adapted to hold said cup leveler at one end of its path of movement, and means on said plate adapted to be contacted by said handle to cause said locking rods to slide into locking engagement with said blocks to hold the plate locked to the container.

12. A cup dispenser comprising a cup container, a closure plate movably connected thereto, a cup leveling member slidable on said closure plate projections secured in said container, cam members secured to said plate, locking rods slidably engaged with said cam members, a handle integrally connecting said locking rods and adapted when moved in one direction to co-act with said cam members to cause retraction of the locking rods out of locking engagement with said projections, and lugs mounted on said 125 130

plate in the path of movement of said handle to cause said locking rods to move into locking engagement with said container projections when the handle is swung in an opposite direction to engage around said cup leveling member to hold the same locked against movement.

13. A cup dispenser comprising a cup container, a closure plate therefor, a cup leveler 10 slidably mounted thereon, locking members on said plate, a handle member connecting said locking members and adapted in one position to engage and hold the cup leveler locked against movement, and members 15 rigidly secured on said plate adapted to connect with said handle member to cause movement of the locking members into and out of locking engagement with the cup container depending upon the direction of movement 20 of said handle member.

14. A cup dispenser comprising a mounting plate adapted to be secured on a wall, a stop plate formed on one end thereof, a cup container pivoted on said mounting plate, a 25 closure for the back of said container, a cup supporting shelf in said container, and a resilient member secured to said shelf adapted to abut against said stop plate when the container is moved into open position to hold 30 the container in a slightly inclined position ready for filling.

15. The combination with a support, of a pivotally supported cup container thereon, and a looped spring member secured on the bottom thereof adapted to contact said support for holding the container in a slightly inclined position with respect to the horizontal when the container is lowered for filling. 35

16. A cup dispenser comprising a mounting plate having an integral stop plate 40 formed thereon, a cup container pivotally supported on said mounting plate, a cover on said mounting plate adapted to hold the cup container in a closed position for use, and a member secured on the bottom of the container adapted to abut said stop plate to resiliently hold the container in an open position for filling when the cover is raised and the container is lowered. 45

17. A cup dispenser comprising a mounting plate, a cup container pivotally supported thereon, a back plate for the container pivoted on said mounting plate between the container and said mounting plate, a container cover pivoted on said mounting plate, 55 and members secured on said cover for frictionally engaging the container and said back plate when the cover is lowered to close the container.

In testimony whereof I have hereunto subscribed my name.

WILLIAM B. MANGOLD.
